BREAKER POINT ASSEMBLY

Victor W. Thomas, Waukegan, Ill.

Application April 5, 1941, Serial No. 386,997

4 Claims. (Cl. 200—30)

My present invention relates to the provision of a breaker point assembly for distributors for ignition systems for internal combustion engines, meaning thereby the provision of a design for a structure including both breaker points and their respective mountings which may be manufactured, assembled and interadjusted completely in a factory so that such assembly may be associated with the breaker plate of a distributor as a unit structure.

The breaker points are those parts of the primary circuit of an ignition system which are opened to cause the collapsing of the field in the coil which generates the current or potential that causes the spark necessary for the ignition of the fuel in the cylinder of the motor. Obviously questions of timing are involved and these parts must be capable of critical precision operation. Heating, and not infrequently some degree of sparking, occurs at the breaker points which, sooner or later, causes their pitting which, together with displacement from other causes, disturbs the registry of, and contact between, the points and seriously affects the resistance of the circuit and the efficiency of its operation. The pivot for the arm carrying the movable breaker point receives the blow or impact from the rotor and the almost as quick action of the return spring on opposite sides which deform the pivot and prevent a fit with a new replacement arm. The adjustment of the return spring is also critical as a weak tension will cause a lag in the functioning of the device and a too strong tension will result in a bouncing or vibration between the meeting points which will also affect contact and the resistance of the circuit.

It has been my object to provide a structure which may be assembled with a breaker plate, either originally or as a replacement, without the necessity of any adjustment between the points themselves or the points and the plate and, of course, it has also been my object to save the exercise of the skill and knowledge necessary in making such adjustments and the time involved in the making thereof.

I have attained the foregoing objects by means of the structure illustrated in the accompanying drawing in which—

Fig. 1 is a plan of a breaker plate in association with a breaker point assembly embodying my invention;

Fig. 2 is a plan of the breaker plate shown in Fig. 1 with the breaker point assembly removed;

Fig. 3 is a plan of the breaker point assembly removed from the breaker plate;

Fig. 4 is a section, to an enlarged scale, along line 4—4 in Fig. 1 and

Fig. 5 is a section, also to an enlarged scale, along line 5—5 in Fig. 1.

Similar reference characters refer to similar parts throughout the several figures.

In a conventional form of distributor the breaker plate 10 is mounted for rotative movement in the distributor casing (not shown) about the rotor (also not shown) which protrudes through the central opening in the breaker plate. I provide in the breaker plate a circular aperture 11, as shown in Fig. 2. My breaker plate is similar to the conventional form of breaker plate, heretofore referred to, except that instead of the aperture 11 the conventional breaker plate is fixedly provided with a pin upon which swings the arm carrying the movable breaker point.

I provide a bracket 12 having at one end an extension 13, at right angles to the plane of the bracket, carrying the fixed or stationary breaker point 14. At the other end the bracket 12 is perforated, and in the perforation is fixedly mounted a stud or post, the lower end 15 of which extends below the bracket 12 and into the aperture 11 in the breaker plate for the purpose of partially orienting or locating the breaker point assembly with the breaker plate. The other locating means comprises an elongated aperture 16 cooperating with the eccentric 17, as most clearly seen in Fig. 4. As will be seen by reference to Fig. 1, the rotation of the eccentric 17 will advance toward or withdraw from the rotor the striker block hereafter to be described. The bracket is secured in desired position by means of a machine screw 18 passing through an additional aperture 19 in the bracket 12 and screwing into the breaker plate as shown in Fig. 4. The stud or post is enlarged at 20 to contact the upper surface of the bracket 12, and above the enlargement 20 the stud or post is reduced to provide a pintle 21 for the arm carrying the movable breaker point. Adjacent the top the pintle is circumferentially grooved to receive a split washer 22 for holding the arm in assembly with its pintle.

The arm which carries the movable breaker point 23 in one end comprises a formed stamping 24 in the other end of which is mounted an electrically insulating bushing 25 and an end 55 of the return spring 26. About midway of the

length of the arm 24 is secured an electrically insulating breaker block 27.

In the conventional structure the end of the return spring is anchored to a projection arising from the breaker plate, but in my assembly I form a projection 28 from the edge of the bracket 12 which extends at right angles to the plane thereof. This projection is bored and within the bore is mounted an insulating bushing 29, through which passes a nut 30 for securing the end of the returning spring 26 and a pair of metal washers 31-31 between which washers may be secured the end of the conductor (not shown) of the primary circuit of the ignition system.

It may be argued that with the former arrangement it was only necessary to replace the movable breaker point and the arm upon which it was mounted whereas with my assembly both breaker points and their respective mountings are replaced. With my structure, however, the parts are assembled under factory conditions with the advantage of close inspection and there can be no question of the fit of a new arm with a worn pivot or the adjustment of the tension of the return spring. The cost of experienced, skilled labor at the repair shop is much greater than the entire replacement. Moreover, it hardly ever occurs that when the movable breaker point is pitted or otherwise damaged to an extent needing replacement that the fixed breaker point is not also damaged to some extent.

Having described my invention, what I claim as new and desire to secure by Letters Patent is—

1. A breaker point assembly in combination with a breaker plate having a perforation therein for the location of said assembly, a fixed breaker point and a bracket upon which said point is mounted, a stud fixedly mounted in said bracket and extending on opposite sides thereof to enter the perforation in said breaker plate and to form a pintle for the movable breaker point arm, means for swinging and fixing the movable end of said bracket nearer to and farther from the center of said breaker plate, a projection produced from the edge of said bracket for anchoring an end of the spring for returning the movable arm and the breaker point carried thereby to contact with the fixed breaker point, an arm mounted upon said pivot, a breaker point carried by said arm, a striker block secured to said arm and a return spring fixed to said arm and extended and secured to the said anchoring projection from said bracket.

2. A breaker point assembly comprising a

bracket having an elongated and a round perforation therein and a pair of developments extending at right angles to the plane and from one end and a side thereof, a stud fixed in and extending from opposite faces of said bracket to provide respectively locating projection therefor and a pintle, a breaker point mounted on the development at the end of said bracket, an arm, an insulating bushing mounted in one end thereof of cooperating with said pintle, a breaker point mounted in the other end of said arm to register with said other breaker point, a striker block secured to said arm, a return spring mounted upon said arm adjacent the location of said insulating bushing, the extending end of said spring insulated from and anchored to the development extending from the side of said bracket, and means cooperating with said elongated and round perforations to adjust and fix said assembly radially with respect to the point of location fixed by said locating projection.

3. A breaker point assembly comprising a bracket having adjacent one end and on one side developments extending at right angles to the plane of said bracket, a breaker point mounted upon the development adjacent one end, a post or stud mounted upon the other end of said bracket and extending on opposite sides thereof, mounted upon an extending part of said post or stud as a pivot, an arm electrically insulated from said bracket, a breaker point carried by said arm, a spring fixedly secured to and extending from the pivoted end of said arm and means for securing the opposite end of said spring to and electrically insulating it from the development arising from a side of said bracket.

4. A breaker point assembly comprising a bracket having developments extending at right angles to the general plane thereof, a contact point mounted upon one of said developments, means for anchoring a spring to and insulating it from said other development, a stud fixedly secured to said bracket and extending upon opposite sides thereof, an arm, a contact point mounted upon said arm, an insulating bushing carried by said arm and receiving the portion of said stud projecting from the side of said bracket as a pintle, a spring carried by said arm the other end of which is engaged by said anchoring means, the end of said stud projecting from the face of said bracket opposite said arm being adapted to cooperate with an aperture in a breaker plate for assisting in locating said bracket therewith.
